UNITED STATES PATENT OFFICE.

JOHN HAROLD MACGREGOR, OF PORTLAND, OREGON.

EQUALIZED ROLLER PRESS FOR PIPE MANUFACTURING.

Application filed June 12, 1925. Serial No. 36,764.

To all whom it may concern:

Be it known that I, JOHN HAROLD MACGREGOR, a citizen of the United States, residing at city of Portland, in the county of Multnomah and State of Oregon, have invented certain new and useful Improvements in Equalized Roller Presses for Pipe Manufacturing, of which the following is a specification.

10 The present invention relates to a roll press for the manufacture of pipes, and has for its object to provide a structure whereby the lock bars may be crimped into engagement with the semi-cylindrical sections of 15 the pipe.

Another important object of the invention is to provide a device of this nature which is exceedingly simple in its construction, efficient and reliable in operation, strong, 20 durable, easy to manipulate, not likely to easily become out of order, and otherwise well adapted to the purpose for which it is designed.

Another very important object of the invention is to provide a press of this nature having a structure whereby the pressure is equalized between top and bottom bar rolls so that the lock bar will be crimped with equal pressure at its inner and outer sides.

30 With the above and numerous other objects in view, as will appear as the description proceeds, the invention resides in certain novel features of construction, and in the combination and arrangement of parts 35 as will be hereinafter more fully described and claimed.

In the drawing:—

Figure 1 is a side elevation of the device, embodying the features of this invention.

40 Figure 2 is a front elevation thereof, and

Figure 3 is an enlarged fragmentary transverse section taken through the pipe being manufactured.

45 Referring to the drawing in detail, it will be seen that the numerals 5 designate the two sides of the press, which extend vertically in spaced relation to each other, so as to be disposed in a parallel plane. A top platen 6 is mounted between the upper ends of the sides 5 and a bottom platen 7 is fixed between the bottom ends of the sides 5. A bracket 8 depends from the platen 6 and supports press rolls 9. A ram 10 operated mechanically, by a hydraulic pressure or in 50 any other manner is slidable through the platen 7 and has a bracket 11 on its upper

end for supporting the press rolls 12. A pair of horizontally disposed and vertically spaced bracket arms 13 extend inwardly from each side 5 and have journaled in their ends, in any suitable manner pipe guide rolls 14, the axis of which extend vertically. The sides 5 are provided with guide slots 15, extending vertically thereof along the median vertical dimensions thereof, and 65 terminate a distance from the top and bottom thereof. Journal boxes 16 are slidable in the guide slots 15 and receive a shaft 17 having the top crimping roll 18 mounted thereon. The press rolls engage the shaft 70 17 and are disposed one on each side of the crimping rolls 18. A similar pair of journal boxes 19 are slidable in the lower portions of the slots 15 and receive shaft 20, which is engageable by the press rolls 12 and has 75 mounted on its center portion the crimping roll 21. Threaded bars 23 and 24 extend respectively from journal boxes 16 and 19, through the top and bottom ends of the sides respectively, and nuts 25 and 26 are 80 engaged on the bars 23 and 24 respectively, for resting against the respective ends of the slots 15, so that the approximate adjustment may be made between the shafts 17 and 20 before the ram 10 is brought into 85 play. A pipe mandrel 28 is mounted to move between the crimping rolls 18 and 21 and between the guide rolls 14. Lock bar guide rolls 29 are mounted in spaced relation along the upper edge of the pipe mandrel. At the end of the pipe mandrel there is journaled intermediate crimping rolls, two in number, as indicated at 30, and these rolls 30 are received in the ends of the pipe mandrel, said end being bifurcated for 95 this purpose.

In using the device, the semi-cylindrical pipe sections 32 are disposed on one each side of the pipe mandrel and have their edges disposed in the grooves 33 of the lock 100 bar 34. The pipe mandrel 28 is then fed between the sides 5, as previously indicated, in any suitable manner, either manually or by suitable mechanical means, and thus the top and bottom lock bars 34 are engaged 105 with by the top and bottom crimp rolls 18 and 21 respectively, on their outer sides, and by the intermediate crimping rolls 30 on their inner sides, so that when the ram 10 is brought into play the side bars of the 110 grooves 33 of the lock bars 34 will be crimped into locked engagement with the

edges of the pipe sections 32. Any suitable means (not shown) may be used to drive crimping rolls 18 and 21.

It is thought that the construction, operation, and advantages of the invention will be clearly understood by those skilled in this art, without a more detailed description. It is desired, however, to point out that the present embodiment of the invention has been disclosed merely by way of example, and that numerous changes in the details of construction, and in the combination and arrangement of parts may be resorted to, without departing from the spirit or scope 15 of the invention as hereinafter claimed, or sacrificing any of its advantages.

What is claimed as new is:

1. A roller press for pipe manufacturing including a pair of sides, a top platen between the sides, a bottom platen between the sides, a bracket depending from the top platen, press rolls journaled in the bracket, a ram slideable through the bottom platen, a bracket on the upper end of the ram, press 25 rollers journaled in the bracket on the ram, a pair of journal boxes slidably mounted in each side, means for adjusting the journal boxes toward each other, a pair of shafts disposed transversely between the sides and 30 mounted in the journal boxes, crimping rolls one on each shaft, said shafts being engageable with the adjacent press rolls so that said rolls are disposed one on each side of the respective crimping rollers, a pair of 35 guide rolls having their axes extending rectangularly to the axes of the shafts, and means for mounting the guide rolls on the sides.

2. A roller press for pipe manufacturing 40 including a pair of sides, a top platen between the sides, a bottom platen between the sides, a bracket depending from the top platen, press rolls journaled in the bracket, a ram slideable through the bottom platen, a bracket on the upper end of the ram, press 45 rollers journaled in the bracket on the ram, a pair of journal boxes slidably mounted in

each side, means for adjusting the journal boxes toward each other, a pair of shafts disposed transversely between the sides and 50 mounted in the journal boxes, crimping rolls one on each shaft, said shafts being engageable with the adjacent press rolls so that said rolls are disposed one on each side of the respective crimping rollers, a pair of 55 guide rolls having their axes extending rectangularly to the axes of the shafts, means for mounting the guide rolls on the sides, a pipe mandrel extending rectangularly to the axes of the shafts and the guide 60 rolls, and a pair of intermediate crimping rolls journaled in the end of the pipe mandrel for association with the other crimp rolls.

3. A roller press for pipe manufacturing 65 including a pair of sides, a top platen between the sides, a bottom platen between the sides, a bracket depending from the top platen, press rolls journaled in the bracket, a ram slideable through the bottom platen, 70 a bracket on the upper end of the ram, press rollers journaled in the bracket of the ram, a pair of journal boxes slidably mounted in each side, means for adjusting the journal boxes toward each other, a pair of shafts 75 disposed transversely between the sides and mounted in the journal boxes, crimping rolls one on each shaft, said shafts being engageable with the adjacent press rolls so that said rolls are disposed one on each side of 80 the respective crimping rollers, a pair of 85 guide rolls having their axes extending rectangularly to the axes of the shafts, means for mounting the guide rolls on the sides, a pipe mandrel extending rectangularly to the axes of the shafts and the guide 90 rolls, a pair of intermediate crimping rolls journaled in the end of the pipe mandrel for association with the other crimp rolls, and guide rolls journaled on the upper edge of 95 the pipe mandrel.

In testimony whereof I affix my signature.

JOHN HAROLD MacGREGOR.
